UNITED STATES PATENT OFFICE.

EUGENE T. TURNER, OF NEW YORK, N. Y., ASSIGNOR TO AMERICAN PLAYER ACTION COMPANY, A CORPORATION OF WEST VIRGINIA.

AUTOMATIC TRACKER FOR PIANO-PLAYERS.

1,250,722.

Specification of Letters Patent. Patented Dec. 18, 1917.

Application filed August 22, 1914. Serial No. 858,039.

To all whom it may concern:

Be it known that I, EUGENE T. TURNER, a citizen of the United States, residing in the city, county, and State of New York, have invented certain new and useful Improvements in Automatic Trackers for Piano-Players, of which the following is a specification.

My invention aims to provide certain improvements in means for automatically insuring the correct tracking of the music sheet in piano players and similar instruments.

The accompanying drawings illustrate an embodiment of the invention.

Figure 1 is a front elevation of the spool box and related parts;

Fig. 2 is a plan of the same;

Fig. 3 is a horizontal section of the pneumatic or bellows;

Figs. 4 and 5 are horizontal sections of the driving and the driven music roll spindles.

The music roll A is located between a driving spindle B and a free spindle C; the roll A having a notch which fits a squared end B' of the driving spindle B and having a tapered recess at the opposite end to fit the spindle C. The latter is adapted to yield to the left, as hereinafter described, to permit the introduction of the music roll. The music passes from the music roll A to the feeding or winding-on roll D which is constantly driven, so that the music sheet passes over the tracker board E in a downward direction. The note openings F' in the sheet should register with the openings F in the tracker bar and this invention provides a mechanism for maintaining correct registration.

In my Patent No. 1,198,291 dated Sept. 12, 1916, I have described a mechanism for accomplishing this purpose and have illustrated the same by means of a tracker which is shiftable to the right or to the left to maintain its note openings in register with those of the sheet. The present invention provides a mechanism for shifting the music roll A and thus shifting the sheet to bring it in correct register with the tracker, the latter being fixed.

The control is effected by the passage of the edge of the sheet over a guide-opening G which is located at any suitable point over which the margin of the sheet passes. In

the present case the guide-opening is formed in a block H located at the end of the tracker board E and adjustable to the right and left by means of a knurled nut J exposed at the front of the apparatus, this being the same arrangement of the guide-opening as is described in my application above referred to and also in my Patent No. 1,056,858.

The edge of the music sheet K will always run over the guide-opening G so as to maintain the latter partially covered and to permit a passage of air therethrough. A tube L (Fig. 2) passes from the guide-opening G to a bellows or pneumatic L' which is fixed on the back of the spool box, the tube L leading to a passage M which communicates with the interior of the bellows. The bellows is provided with an outlet passage N covered by a bleed hole O and communicating through a pipe P with a vacuum or wind chest Q in which a vacuum is constantly maintained during the operation of the player. As the uncovered area of the guide-opening G becomes greater or less than the area of the bleed hole O the bellows will expand by the increase of pressure (lessening of suction) or contract by the lessening of pressure (or increase of suction).

The spindle C which receives the left hand end of the music roll is constructed to yield and to press the roll to the right into engagement with the spindle at the opposite end and to exert a pressure ultimately upon the bellows to expand the same. The spindle C is shouldered as indicated in Fig. 5 and bears against a spring R within a housing carried in the side T of the spool box. A collar U limits the outward movement of the spindle. The opposite spindle B passes through the opposite side V of the spool box and is supported by bearing arms W and X which project forward from a casting Y which is fastened on the right hand wall V of the spool box and which carries the mechanism for winding and rewinding.

The spindle B is splined in a wheel Z which serves as a brake wheel and which has a tooth *a* for engagement with a clutch. The brake or clutch wheel Z is formed with a grooved hub *b* projecting at one side, the groove of which is engaged with a pin *c* (Fig. 2) projecting forward from the casting Y which carries the driving gear; so

that the wheel Z is free to rotate, but not to move longitudinally. A clutch d is mounted to rotate and to slide on the spindle and is formed with a groove engaged by the prongs 5 of a fork e mounted on a clutch operating lever f. The clutch ring d is connected with a sprocket wheel g driven constantly from the motor shaft through a chain h. On the outer end of the spindle B is a collar j fastened by a set screw and adapted to limit the inward movement of the spindle B by 10 striking the bearing X.

The spindle B, when there is a roll of music in the machine, is pressed always to 15 the right by means of the spring on the opposite spindle C. In the playing of a sheet of music the clutch d is in the right hand position so that the spindle allows the roll to turn freely as the music sheet is drawn 20 off it by the winding roll. After a sheet has been played the clutch is shifted to the left sufficiently to bring it into contact with the pin a on the wheel Z so that the latter, and through it the spindle B, are turned 25 backward to rewind the sheet on the roll.

The bellows L' in its collapsing movement tends to press the spindle B and the music roll to the left against the resistance of the spring acting on the spindle C. An arm k 30 is mounted on the movable member of the bellows and extends beyond the same to a point to the right of the wall V of the spool box. Near its end a link l passes through it and carries a button m with a curved 35 face bearing against the lever, the button being screwed on the end of the link to secure any desired adjustment. The link passes through the back n of the spool box and is pivotally connected to an arm o of a 40 lever which is pivoted at p upon the top of the casting Y and which has an obliquely and forwardly projecting arm q, the end of which is provided with a downwardly projecting arm r which engages the rounded 45 outer end of the spindle B.

As the sheet travels downward over the tracker bar its edge normally covers a portion of the guide-opening G. There is a constant suction in the bellows and air is 50 therefore sucked in through the uncovered portion of the guide-opening. If the sheet shifts to the right it covers a greater area of the guide-opening, air is admitted to the bellows L' slower than it is withdrawn 55 through the bleed opening O, the force of the suction within the bellows is increased, the arm k is swung outward or to the rear, pulling the link l and arm o in the same direction, the arm q and its depending flange 60 r are shifted to the left and the spindle B and music roll A are pushed to the left, the spring spindle C yielding in proportion to the increased force exerted by the bellows, and thus the sheet is shifted to the left to 65 correct the divergence which occurred. On

the other hand, if the sheet shifts to the left beyond the exactly balanced position it uncovers a greater area of the guide-opening, admits air to the bellows faster than it is sucked through the bleed hole, the suction 70 of the bellows is lessened and the spring forces the spindle C and music roll A to the right sufficiently to correct the divergence which occurred. In theory there is a constant error and correction, but in practice 75 the correction occurs practically simultaneously with the occurrence of the error so that the path of the edge of the sheet instead of being a broken or waving line is a straight line. 80

As the sheet has a wider or a narrower margin the block H carrying the guide-opening G is shifted to the right or to the left, the tube L being flexible to permit such movement. This movement, however, 85 is very slight. The adjustment, if any is necessary, is made at the beginning of the passage of a roll of music and is not thereafter altered for that roll.

The apparatus is adapted to be used with 90 a variety of driving gears. In the construction illustrated the winding-on roll has on one end a gear wheel s meshing with a pinion t having long teeth, so as to be in engagement in all positions of adjustment and mounted 95 loosely on the driving shaft u upon which is splined a hub v having a groove engaged by a fork in the lower end of the clutch lever f and carrying a sprocket wheel w which drives the chain h. The shaft u is 100 coupled to the constantly driven shaft z of the motor so that the lower sprocket wheel w, chain h and upper sprocket wheel g, with clutch rings, are constantly rotated. When the clutch lever f has its lower end swung 105 to the left then the lower clutch ring engages the pinion t and drives the winding-on roller, the music roll spindle B being left free to rotate except as it braked by the usual brake y bearing against the brake 110 wheel Z. When the clutch lever has its lower end shifted to the right the pinion t, gear s and winding-on roll D are left free to rotate backward, and the brake wheel Z is engaged by the upper clutch and rotated, 115 turning the spindle B and music roll backward to rewind the sheet.

A portion of the sheet is shown in Fig. 1 with one of its perforations F' registering with the proper perforation F in the tracker 120 bar. The apparatus is of extreme simplicity and can be applied to existing players with almost no alteration of the remaining mechanism. It is only necessary to make the spindle B slideable in its bearings and to add 125 the simple bellows L at the back of the frame and the lever and link connections with this bellows to the exposed ends of the spindle B. The location of the bellows L upon the back of the frame permits of bring- 130

ing it very close to the guide-opening G so that the passage L between them is extremely short and the response of the bellows to any variation in the uncovered area 5 of the guide-opening is very quick. The bellows also is located close to the spindle B upon which it is to operate so that the connecting parts are extremely light and simple. The spring which is already common 10 for the spindle C is put to an additional use in pressing constantly against the collapsing force of the bellows. The only tracking mechanism visible to the user sitting in front of the machine (see Fig. 1,) is the small 15 lever o q; so that in appearance it is far simpler and more attractive than other tracking mechanisms in use.

What I claim is—

1. The combination with the spool box of 20 a piano player of tracking control mechanism including a part having a guide-opening, a pneumatic mounted behind the spool box and close to said part and connected by a short passage to said guide-opening so as 25 to respond quickly to any variation in the uncovered area of said guide-opening, a suction device communicating with said pneumatic through a bleed hole of fixed open area, adjusting means at the front of the 30 spool box adapted to adjust the lateral regulation between the sheet and the guide-opening, an arm mounted on the movable member of said pneumatic and located close to and in the rear of said adjusting means,

means for transmitting a collapsing movement of said pneumatic through said arm and adjusting means to the music roll to shift it in one direction, and a spring tending to move the music roll in the opposite direction. 35

2. The combination with the spool box of 40 a piano player of tracking control mechanism including a part having a guide-opening, a pneumatic mounted behind the spool box and close to said part and connected by 45 a short passage to said guide-opening so as to respond quickly to any variation in the uncovered area of said guide-opening, a suction device communicating with said pneumatic through a bleed hole of fixed open 50 area, a music roll spindle B adapted to move longitudinally, a lever engaging said spindle, an arm mounted on the movable member of said pneumatic located close to and in the rear of said lever; a link connecting said 55 lever directly with said arm, so that the collapsing movement of the pneumatic moves said spindle and the music roll in one direction, and a spring tending to move the music roll and said spindle in the opposite direc- 60 tion.

In witness whereof, I have hereunto signed my name in the presence of two subscribing witnesses.

EUGENE T. TURNER.
